SPRAY NOZZLE

Donald P. Glessner, Wooster, Ohio, assignor to
 Akron Brass Manufacturing Company, Inc.,
 Wooster, Ohio, a corporation of Ohio

Application May 21, 1942, Serial No. 443,859

6 Claims. (Cl. 299—143)

This invention relates broadly to nozzles for fire fighting equipment and more specifically to nozzles of the so called fog or vapor type.

The primary object of the invention is to separate the column of water delivered through the hose into a plurality of streams and then violently disrupt such streams and subdivide the separated drops of water under atmospheric pressure so that the atomical spheroids thus formed may float in isolated relation to each other. To this end the nozzle embodies a series of ports which are arranged to effect the initial impingement of certain streams of water discharged therethrough, secondly, the impingement of the resultant spray with a stream discharged through a central opening in the nozzle and finally the impingement of the latter resultant mist with a spray of conical form discharged through a circular opening in the end of the nozzle.

A further object of the invention is to provide a nozzle which is economic of manufacture, sturdy of structure and free from such mechanisms as necessitate adjustment or require repair.

Other objects and advantages more or less ancillary to the foregoing and the manner in which all the various objects are realized will appear in the following description, which considered in connection with the accompanying drawing, sets forth the preferred embodiment of the invention.

Referring to the drawing wherein the preferred embodiment of the invention is illustrated;

Fig. 1 is a longitudinal sectional view of the nozzle embodying the present invention;

Fig. 2 is an end elevation of the nozzle illustrated in Fig. 1;

Fig. 3 is a detailed view, shown upon an enlarged scale of the baffle head illustrated in Fig. 1;

Fig. 4 is a front elevation of the baffle shown in Fig. 3 illustrating the arrangement of the discharge ports therein;

Fig. 5 is a vertical section through a modified form of the nozzle shown in Fig. 1; and

Fig. 6 is a front elevational view of the baffle head employed therein, the drawing being shown on an enlarged scale.

Referring first to Fig. 1, the nozzle comprises a tubular body 10 threaded for engagement with a hose coupling of conventional form and provided as is customary with radially extended lugs 11 to accommodate the use of a wrench or similar tool. The outer end of the body 10 is threaded for the reception of a sleeve 12 formed with a beveled opening 13 in the face thereof which terminates in a counter bore 14 adjacent the inner end thereof. The sleeve 12 is further formed with

an annular rib 15 rearward the counter bore 14, which engages a rib 16 formed in the periphery of a thimble 17 mounted in the body 10. The inner end of the sleeve 12 is recessed for the reception of the packing ring 18 which is provided to arrest the flow of such water as may find its way through the threaded connections between the thimble and sleeve.

The thimble 17 is formed with a cross bar or spider 19, the central portion of which is drilled and tapped to support the threaded stem of a baffle head 20. The body of the baffle, forward the stem, is constructed to form a passageway 21 communicating with the bore of the body 10 and terminating in a circular port 22 defined by the counter bore 14 and the peripheral edge of the baffle head. The edge of the outer end of the baffle is formed with teeth 23 provided to disrupt the spray and subdivide the drops passing through the restricted passage or port 22. The stem of the baffle is drilled throughout its length to form a discharge port 24 which terminates in the center of a conical recess 25 formed in the face of the baffle. Within the recess 25 there is a series of ports 26 drilled to converge in pairs towards each other and towards the central port 24, the inclination of these ports being so arranged as to cause impingement of the respective pairs of streams before such streams reach the column of water discharged through the port 24. Thus as the water is discharged under pressure the streams will be broken into a spray which in turn will be thrown with disruptive force into the jet discharged through the port 24. Since the ports 26 are inclined towards the medial axis of the head and arranged concentric thereto the streams will be disrupted not only by impingement of the water from the convergent pairs of ports but also by impingement of the drops of water circumferential the streams as such drops reach their common focal point and the jet from the port 24. As the mist from the disrupted streams penetrates the axial jet the heavier drops of water therein will be thrown against the conical spray from the circular port 22 with sufficient velocity to effect a further division of the particles of water in both the mist and the spray.

Although, as pointed out above, the mist from the convergent streams impinges the conical spray with disruptive force it should be noted that little if any loss occurs in the velocity of the spray since the direction and rate of flow of both streams of vapor are substantially the same.

From the foregoing it will be seen that atom-

ization of the water occurs beyond the confines of the nozzle where atmospheric pressure acting upon shattered drops will form and hold the minute spheroidal particles in isolated relation with each other.

In the modified form illustrated in Figs. 5 and 6, a second series of ports is provided adjacent the periphery of the baffle, such ports being arranged to converge in pairs divergent the medial axis of the head so that the focal point thereof will impinge the conical spray discharged through the port 30 and thus effect a further subdivision and isolation of the particles of water therein.

When desired the sleeve 12 may be adjusted relative to the baffle head 20 to effect the discharge of a spray or stream of narrow divergence and high velocity so that the column of water thus produced may be projected upon a far distant object.

It will be readily recognized that with the sleeve and/or baffle so adjusted a column of water of tubular form will be discharged from the port 22 which can be positioned to envelop or surround the marginal edges of the objective while the core of mist or fog carried by the stream is focused directly upon the flame.

Although the foregoing description has been directed to a fire hose nozzle it will be understood that the improved ported baffle may be used with equal faculty in spray heads for sprinkler systems or like devices in similar environs.

I claim:

1. A spray nozzle for a fire hose comprising a tubular body having the end portion thereof flared outwardly, a baffle head supported in said body, the end of said baffle being disposed within the flared portion of the body and in spaced relation thereto, said baffle having a central port therein and a plurality of ports in circumambient relation thereto, the last named ports being inclined in pairs towards each other and inclined at a more obtuse angle towards said central port.

2. A nozzle for a fire hose comprising a tubular body having a bell mouthed end, a baffle head disposed within the bell mouthed end of the body and defining a circular port for the delivery of a conical stream, said baffle having a plurality of ports therein inclined toward each other to effect the disruption of the jets delivered therethrough being further inclined to effect the impingement of the spray from the disrupted jets with the conical stream from the circular port.

3. A spray nozzle comprising a tubular body, a baffle head therein, the end portion thereof being disposed in spaced relation with the end of said body to define a circular port for the delivery of a conical stream, said baffle having a central port therein and a plurality of convergent openings, said openings being inclined towards each other in pairs and towards the central port so that the jets discharged therethrough impinge

each other and the resultant spray partially impinges the jet from the central port and partially impinges the divergent conical stream.

4. A spray nozzle comprising a tubular body having a counter bore in the free end thereof, a baffle head supported therein having the end portion thereof disposed in spaced relation with said counter bore, teeth in the portion of said baffle adjacent the counter bore to effect the delivery of a conical divergent spray stream, the walls of

20 the baffle defining a central port and a plurality of concentric openings, certain of the concentric openings being inclined towards each other to effect partial impingement of the streams delivered therethrough and being also inclined to effect the impingement of the resultant spray with the stream delivered through the central port and delivery of the unimpinged portion of the jets from the concentric openings with the divergent conical spray stream.

30 5. A spray nozzle comprising a tubular body, a baffle head therein disposed in spaced relation therewith to define a circular port in the end of the body, said baffle having a central port therein and a plurality of openings arranged in concentric relation thereto, said openings being inclined towards the central port with certain of said openings inclined at sharper angles towards each other, whereby the jets delivered through said openings will merge before impingement with the stream delivered through the central port.

35 6. A spray nozzle comprising a tubular body, a baffle head therein, a flared end portion on said baffle disposed in spaced relation with the mouth of said body and defining a circular discharge 45 port, said baffle having an axial hole therein constituting a central port, and having a plurality of circumambient openings inclined in pairs towards each other, certain of said openings being inclined towards the central port, other of said openings being inclined towards said circular discharge port.

DONALD P. GLESSNER.
